UNITED STATES PATENT OFFICE.

AUGUST RIEBE, OF BERLIN, GERMANY.

BALL-BEARING.

No. 824,819.

Specification of Letters Patent.

Patented July 3, 1906.

Application filed July 13, 1906. Serial No. 269,488.

To all whom it may concern:

I, AUGUST RIEBE, engineer, a subject of the King of Prussia, German Emperor, residing in Berlin, N. W., 5 Kaiserin-Augusta-Alle 30, in the Kingdom of Prussia, Germany, have invented certain new and useful Improvements in Ball-Bearings, of which the following is a full, clear and exact description.

10 The invention relates to improvements in ball-bearings.

In ball-bearings provided with abutment-plates connected by springs these springs are usually in contact with the outer or inner 15 ring over the surface of which they slide. Consequently there is always the risk that said plates may be forced out between the balls, which press against them, and that the spiral springs may be turned over, with the 20 result that as they are no longer controlled by the rounded ball-race they are liable to fall out, thereby naturally endangering the continued regular running of the ball-bearings. Such inconveniences are rendered im- 25 possible in the present new construction.

In the accompanying drawings, which illustrate a ball-bearing constructed according to the present invention, Figure 1 is a front elevation of a part of the cage and intermediate 30 distance-pieces drawn to a large scale. Fig. 2 is a top view of a single intermediate distance-piece. Fig. 3 illustrates a complete bearing, partly in section, constructed according to the present invention. Fig. 4 is a cross-section through a distance-piece.

The separate intermediate distance-pieces include boxes consisting of two U-shaped bent plates *f* and *e*, sliding by their limbs telescopically one within the other, and with- 40 in the box thus formed is a spiral spring *h*, provided with a lubricating or felt insertion or cove *i*. The sliding connection between the plates insures their parallelism and a normal pressure on the spring in all positions 45 of the plates. The expanding tendency imparted to the plates *e* and *f* by the spring *h* is, as shown in the drawings, limited by the stays or straps *l* and *k* of the cage-ring *c*.

The stays or straps *l* and *k* lie in grooves or 50 notches in the plates *e* and *f* in such manner that the expansive movement imparted to the latter by the spring *h* is limited by the shoulders or edges of said grooves or notches, and the contractile movement of said plates 55 is also limited by the arrangement that the

ends of the two arms or limbs of the plate *e* when the plates are pressed together come against the other plate *f*.

It would of course also be possible to limit said movements by forming the grooves or 60 notches in the plates *e* and *f* of suitable width with relation to the stays or straps *l* and *k*. The abutment-plates *e* and *f* are thus no longer mechanically connected with the spring *h*; but they are supported and guided by the 65 stays or straps *k* and *l* of the cage-ring *c*. The springs *h* do not come into contact with the ball-race, and thus are not connected with parts moving relatively to said springs, and the turning over or falling out of the springs 70 is thus rendered absolutely impossible.

Inasmuch as the separate intermediate boxes are mounted on the same ring, the cage forms a compact whole, which can be easily taken out and the boxes withdrawn from be- 75 tween the balls after removal of the clasp-ring *g*. This arrangement has the advantage of overcoming the difficulty of dismounting the intermediate boxes separately, which operation was very troublesome and caused 80 great loss of time, as the removal of the ring *g*, (which by its natural spring-like action, aided during the running of the shaft, axle, or the like by centrifugal force, takes firmly under the hook-shaped extensions of the stays 85 or straps *l* of the cage,) can be effected without difficulty and without the aid of any instrument. The straps *l* may be either at the outer edge of the cage, as shown in Figs. 1 and 2, or at the inner edge, as shown in Fig. 3. 90

In order to protect the parts of the cage above described from wear and tear through rubbing against the inner or outer ring, plates *d* are provided, which only serve the purpose of bearing-surfaces, so that any sliding of the whole cage construction can only take place between these plates and the rings, and hence only the plates *d* are exposed to wear and tear. Said plates *d* may be made of material which is only liable to be slightly 95 affected by the wear and tear under the strain to which they are subjected. It is, however, possible by using tempered steel plates to reduce the wear and tear to what is for all practical purposes a negligible quantity. It will 100 be understood that cages constructed according to the present invention may with certain modifications be employed in connection with other bearings without departing from the principle thereof.

What I claim as my invention, and desire to secure by Letters Patent, is—

1. In a ball-bearing, a distance-piece between adjacent balls comprising a spring, end plates inclosing said spring, and means for holding said end plates parallel to each other while permitting movement thereof toward and from each other.
2. In a ball-bearing, a cage-ring, a distance-piece between adjacent balls and supported by said ring, and a clasp-ring connected to said cage-ring.
3. In a ball-bearing, a distance-piece having end plates, means for connecting said plates so that they can slide toward and from each other, and means for holding said piece in position between the balls.
4. In a ball-bearing, a distance-piece having end plates, and means for holding said piece in position between the balls, said means permitting said plates to move toward and from each other.
5. In a ball-bearing, a distance-piece having end plates, means for holding said piece in position between the balls, said means permitting said plates to move toward and from each other, and means for limiting such movements.
6. In a ball-bearing, a distance-piece having end plates, comprising two U-shaped members adapted to slide relatively to each other, a spring interposed between such members, and means for limiting the movements of said members.
7. In a ball-bearing, a distance-piece having relatively sliding end plates, and a cage-ring having portions interposed between such plates and adapted to support the same.
8. In a ball-bearing, a distance piece having relatively sliding end plates, a cage-ring having portions interposed between such plates, and adapted to support the same, and a plate *d* between such distance-piece and said ring.
9. In a ball-bearing, a distance-piece comprising two plates *e* and *f*, having portions sliding upon each other, such portions having depressions on their upper and lower sides, and a cage-ring having portions *k* and *l* entering such depressions for supporting such piece and limiting the movements of such plates.

In witness whereof I have hereunto signed my name in the presence of two subscribing witnesses.

AUGUST RIEBE.
